UNITED STATES PATENT OFFICE.

WILLIAM KERR, OF PHILADELPHIA, PENNSYLVANIA, ASSIGNOR TO VAN DEVENTER & HORNE, OF NEW YORK, N. Y.

DESIGN FOR A CARPET.

SPECIFICATION forming part of Design No. 13,802, dated March 20, 1883.

Application filed February 15, 1883. Term of patent 3½ years.

To all whom it may concern:

Be it known that I, WILLIAM KERR, of Philadelphia, in the State of Pennsylvania, have invented a new Design for Carpets, of which the following is a specification.

The groundwork of this design is mottled with small rectangular figures. The pattern is composed of sprigs or leaflets and stems a b c d, interspersed between the main figures, e e, which are bunches composed of central flowers, leaflet designs f, grasses, and heads of grain at g.

The carpet with the aforesaid designs forming the pattern thereof is shown in the accompanying photograph.

The patterns are repeated at intervals, as shown, and are placed diagonally to each other, as shown.

I claim as my invention—

The design for carpet pattern, composed of the sprigs a b c d, and the bunches of flowers, leaflets, and heads of grain e f g, substantially as represented.

Signed by me this 9th day of February, A. D. 1883.

WILLIAM KERR.
